(57) **CLAIM**

The ornamental design for a humidifier, as shown and described.

DESCRIPTION

FIG. 1 is a front perspective view of a humidifier showing my new design;

FIG. 2 is a top plan view thereof;

FIG. 3 is a front elevation view thereof, on a reduced scale;

FIG. 4 is a left side elevation view thereof, on a reduced scale;

FIG. 5 is a right side elevation view thereof, on a reduced scale; and,

FIG. 6 is a rear elevation view thereof, on a reduced scale. The bottom view (not shown) forms no part of the claimed design. The subject matter shown in broken lines forms no part of the claimed design.
